US0D1034367S

(12) **United States Design Patent** (10) Patent No.: **US D1,034,367 S**
(45) Date of Patent: ** Jul. 9, 2024

(54) **FAIRING FOR MOTORCYCLES**

(71) Applicant: **PIAGGIO & C. S.P.A.**, Pontedera (IT)

(72) Inventors: **Marco Lambri**, Pontedera (IT); **Marco Canepa**, Pontedera (IT)

(73) Assignee: **PIAGGIO & C. S.P.A.**, Pontedera (IT)

(**) Term: **15 Years**

(21) Appl. No.: **35/517,216**

(22) Filed: **Nov. 16, 2022**

(80) **Hague Agreement Data**

Int. Filing Date: **Nov. 16, 2022**

Int. Reg. No.: **DM/225074**

Int. Reg. Date: **Nov. 16, 2022**

Int. Reg. Pub. Date: **May 19, 2023**

(57) **CLAIM**

The ornamental design for fairing for motorcycles, as shown and described.

DESCRIPTION

2.1 is a front perspective view of a fairing for motorcycles embodying our new design;

2.2 is a front elevation view thereof;

2.3 is a rear elevation view thereof;

2.4 is a right-side elevation view thereof;

2.5 is a left-side elevation view thereof;

2.6 is a top plan view thereof; and

2.7 is a bottom plan view thereof.

Portions shown in broken lines illustrate parts of the fairing for motorcycles that form no part of the claimed design.

1 Claim, 7 Drawing Sheets
